UNITED STATES PATENT OFFICE.

CARL SMULDERS, OF LIEGE, BELGIUM.

PIANO ACTION.

Application filed January 19, 1925, Serial No. 3,425, and in Belgium February 13, 1924.

The present invention has for its object a piano action, in which improved means are provided for projecting and releasing the hammer in such a manner, as to permit the latter to efficiently and rapidly repeat its stroke or strokes against the string.

The object of the present invention may be applied as well to grand pianos and to upright pianos as to player pianos.

10 The annexed drawing represents by way of example:

Figure 1 the essential parts of a piano-action-unit as used in connection with grand pianos, constructed according to the 15 present invention.

Figure 2 the essential parts of a piano-action-unit, as used in connection with upright pianos, constructed in accordance with the present invention.

20 According to Figure 1, the action unit comprises the following usual parts: a hammer 1, pivoted at 1' to the hammer support 1"; a key 2, having its fulcrum at 3; an adjusting screw called the pilot 4 fixed upon 25 the inner end of the key 2; a guiding link 5, pivoted at 5' to the corresponding support 5"; an adjustable releasing screw 6 within the hammer support 1"; a jack 7 pivoted at 8 to the guiding link 5; said jack 30 being formed with a projecting part or finger 7' acted upon by the compressible spring 11, which latter provokes the jack to bear against the jack-rest 9.

A usual pushing rod 12 may be provided 35 upon the hammer rod 1, to cooperate with the spring 11. However, according to the object of the present invention this pushing rod may be readily dispensed with.

In the usual piano actions, the jack is 40 provided with a pin or spur which enters into contact with the releasing screw, as soon as the hammer head arises at a distance of about 2 or 3 millimeters from the string. Now, the inner or rear end of the 45 key must continue its upward movement, as the releasing movement of the jack depends from this upward movement of the rear end of the key. However, in the piano actions known up to this time, the guiding link, as well as the jack participate in 50 this last mentioned ascending movement of the rear end of the key. Moreover in the

usual piano-actions, this common ascending movement of the mentioned parts must exceed the ratio which would be sufficient to 55 provoke the releasing movement of the jack, in order to approach the hammer rest to the hammer head, which hammer rest is secured to said inner end of the key. Thus when the inner end of the key terminates its ascending movement, the summit of the jack is disposed at a considerably higher level than at the movement in which the spur of the jack entered into contact with the releasing screw. This is the 60 ground of the difficulty to construct a perfectly well operating piano action, because the exceedingly raised position of the jack hinders the hammer to efficiently fall back after the stroke, the necessity of obviating 65 these inconveniences being the reason why the usual piano actions are so complicated in construction.

According to the present invention all these difficulties are obviated in a novel simple and very efficient manner. According to the object of the present invention it is not the mentioned spur of the jack which is arrested or stopped, but the guiding link itself. Thus, as soon as the guiding link 75 is arrested, only the inner end of the key continues to move upwards, whereas the guiding link remains in its stopped position, that is to say, at the same level, the summit of the jack executing at the same 80 time a descending movement, by virtue of a rocking movement of the jack upon the arrested guiding link. It is evident, from the preceding explanation that the arresting of the combined guiding link and jack in 85 their upward movement, is of prime importance because it assures an easy releasing of the hammer and the possibility of a rapid stroke repetition.

Moreover, according to the object of the 90 present invention the jack always remains with the hammer in a contact, which permits the hammer to be easily and efficiently projected from all successive positions of the jack.

100 Referring principally to Figure 1 of the annexed drawing, the upper extremity of the jack 7 forms an enlarged and preferably curved head-portion 7", which may be

felts or packed in the usual manner, and which bears against the hammer rod 1, and instead of the usual spur the jack 7 has its lower end formed into a heel-portion 7", against which bears the adjusting screw or pilot 4 of the key 2 in such a manner, or at such a point or points, as to provoke the jack 7 to rock in any predetermined sense about its pivot 8, upon the guiding link 5, and to release the hammer, as soon as the guiding link is arrested in its upward movement. The pivot 5' of the guiding link 5 is disposed at a higher level than the point of contact between the heel-portion 7" of the jack and the pilot screw 4 of the key, in order to reduce friction.

The operation of the action unit according to Figure 1 is as follows: so long as the different parts remain in their normal position, the head portion 7" of the jack bears against the hammer rod 1 at a point A which is situated at any convenient distance from the hammer pivot 1', whereby the initial displacement of the hammer, and consequently the playing, may be effected with great facility, or by what is so called, an easy touch. As soon as the hammer 1 actuated by the key through the medium of the jack 7, rises, the point of contact between the head portion 7" of the jack and the hammer rod 1 approaches the pivot point 1' of this latter. Thus, the hammer 1 is finally acted upon by the jack 7 at a point B, which will be situated at but a very small distance from the pivot 1' of the hammer, the violence of the final impulsion of this latter being thereby considerably increased.

As soon as the hammer head 1''' arrives at a distance of about 2 or 3 millimeters from the string 10, the right hand extremity of the guiding link 5 will be stopped by the adjustable stop screw 6 which is disposed outside the action-unit proper, and thereby readily accessible. Now, as the left hand portion of the key member 2 is continuing to move upwardly, the adjustable screw 4, pressing against the heel-portion 7''' of the jack 7, at a point such as for instance C, will oblige the jack to pivot around its axis 8 in an anti-clockwise sense, and consequently to move with its head portion 7'' in the direction of the hammer head 1'''.

If the key is released, the jack 7 rocks in a clockwise direction, due to the pressure of the spring 11, until it is stopped by the rest 9. An auxiliary pushing rod 12 may be provided upon the hammer-rod 1. This pushing rod moves away from the jack 7 during the projecting movement of the device, whereas during the return movement it approaches the jack and pushes it finally into contact with the rest 9. However, as mentioned above, the pushing rod 12 may readily be dispensed with.

65 By virtue of this rocking or releasing

movement of the jack 7, the summit of the latter will be lowered, this lowering of the jack-summit permitting in its turn the hammer, after its stroke, to fall back at a greater distance from the string than the distance 2 70 or 3 millimeters mentioned above, whereby the hammer is brought into a position, from which it readily and efficiently may repeat its stroke in rapid succession, by but slightly releasing and pressing upon the key. As 75 the summit of the jack remains practically in continuous contact with the hammer rod 1, an efficient stroke repetition will be infallible at any rapidity of playing and from all successive positions of the jack. 80

The action unit for an upright piano represented in Figure 2 acts principally in the same manner as that described with reference to Figure 1. The summit of the jack 7 practically remains in continuous contact 85 with the elongated hammer butt 13, thus ensuring an infallible repetition. In this construction it would also be possible to provoke the releasing movement of the jack 7 by stopping the link member 5. 90

According to Figure 2, however, the key screw 4 or equivalent part, acts directly upon the guiding link 5, which has its pivot at 14, whereas the stop-screw 6 acts upon the projecting part 7' of the jack 7, to provoke this latter to execute its releasing movement at the desired moment. The jack is held in its normal position by the spring 11. 95

What I claim is:

1. In a piano action, a pivotally mounted key, a pivotally mounted hammer, and a pivotally mounted guide-link, in combination with a jack pivotally mounted on said link, bearing against said hammer and engaged by said key, means acting on said link and jack tending to maintain the latter in normal operative position, and a stop limiting the movement of said guide-link, said jack being so mounted on the guide-link and so related to said key as to be rocked about its pivot by the latter in its continued stroke after said link has been stopped to depress the upper end of said jack. 105 110 115

2. In a piano action, a rockably mounted key, a pivotally mounted hammer, and a guide-link mounted to swing in a vertical plane, in combination with a jack rockably mounted on said link, bearing against said hammer and actuated by said key, means acting on said link and jack tending to maintain the latter in normal operative position, a stop for limiting the upward movement of said guide link, and means for rocking said jack after the movement of said guide-link has been arrested to depress the upper end of said jack. 120 125

3. In a piano action, a pivotally mounted hammer having a rectilinear plane face ad- 130

jaçent its pivotal mounting, in combination with a rockably mounted jack having an operative portion engaging said face of said hammer progressively nearer the pivotal mounting of the latter as the hammer approaches the end of its stroke, and adjustable means for causing said jack to rock at

a predetermined point to depress said operative portion thereof.

In testimony whereof, I have signed my name to this specification at Antwerp, Belgium, this 6th day of January, 1925.

CARL SMULDERS.
